UNITED STATES PATENT OFFICE

HERBERT R. STRATFORD, OF CLEVELAND, OHIO, ASSIGNOR TO THE STRATMORE COMPANY, OF CLEVELAND, OHIO, A CORPORATION OF OHIO

SURFACING APPARATUS

Application filed November 16, 1928. Serial No. 319,822.

The present invention, relating, as indicated, to surfacing apparatus is more particularly directed to an improved supporting pad for use in surfacing apparatus of the type now so commonly used for grinding, polishing, buffing and similarly treating surfaces such as panels of wood, metal and other material, and such articles such as castings, automobile bodies, fenders, hoods and the like. The apparatus commonly employed for this purpose consists of a frame or casing provided with handles for an operator and with a projecting shaft, on the end of which is mounted a supporting pad, against which is removably secured a surfacing disk, usually constructed of abrasive adhesively secured to a suitable backing of paper, cloth or some combination of the two. The shaft on which the pad and disk are carried is operated through gearing journaled in the frame or casing and then by a flexible shaft extending to a suitable source of power, although in many cases the operating shaft which carries the pad and disk are operated directly from a self-contained air or electric motor mounted in the frame or casing.

The present invention is directed to a new and improved pad to be used in machines of the above construction and for the purposes, some of which are referred to above. The principal object of the invention is the provision of a simple and inexpensive pad for the purpose described and one which has a more universal application and usefulness than the more specialized and expensive pads which have heretofore been employed, but which have been better adapted to some individual type of surfacing operation than to general operations involving a considerable range of operations.

To the accomplishment of the foregoing and related ends, said invention, then, consists of the means hereinafter fully described and particularly pointed out in the claims; 45 the annexed drawing and the following de-

scription setting forth in detail certain mechanism embodying the invention, such disclosed means constituting, however, but one of various mechanical forms in which the principle of the invention may be used.

In said annexed drawings:—

Fig. 1 is a side elevation of a surfacing apparatus showing my improved abrasive supporting pad in section thereon; and Fig. 2 is a side elevation showing the apparatus of Fig. 1 in operation against a convex surface.

In Fig. 1 I have shown a surfacing apparatus consisting of a frame or casing 1 provided with annularly related handles 2 and 3, of which the handle 3 is hollow and is adapted to receive therein a flexible shaft (not shown) for the operation of suitable connecting gears (not shown) mounted in a casing 1 and adapted to operate a shaft 4 extending from the lower side of the casing. The shaft 4 is adapted to removably receive my improved supporting pad, which will now be described.

My improved pad consists of a circular supporting disk 10 of some tough, resistant, but semi-flexible material, such for example, as rubber cured to a consistency permitting it to flex under severe lateral pressure, but of sufficient rigidity to allow it to be used with relatively little flexibility against flat or convex surfaces. This rubber pad 10 is preferably reinforced by means of one or more layers of some tough fabric 11 embedded in the rearward portion of the pad 10 and extending substantially throughout the area thereof. It is further supported by means of a central reinforcing section 12, which may be formed of a hard relatively inflexible material, such as hard rubber vulcanized to the forward section 10 of the pad, thus making the forward and rear sections of the pad integral with each other.

The supporting portion 12 of the pad is secured to a hub member 13 internally

threaded, adapting it to be removably engaged over the threaded lower end 14 of the shaft 5. The lower portion of the pad 10 is recessed, adapting it to receive an abrasive disk 15 which is held in operative position by means of a locking plate 16 which forces the abrasive disk into the recesses in the pad and is itself engaged with the threaded hollow end of the shaft 14.

10 The action of the present pad against concave surfaces is shown in Fig. 2. When applied to such a surface with considerable lateral pressure the pad is of a consistency to permit it to be flexed or distorted out of 15 its normal plane, allowing it to adapt itself to the curvature of the surfaces to be operated upon, but at the same time there is sufficient resistance to such flexure in the pad to allow the pad to operate both on this type 20 of surface and on relatively flat and convex surfaces. In the latter operation only ordinary pressure is required, due to the resistance of the pad to flexure.

In a pad of the character described intended for a number of different operations 25 and for use against different types of surfaces it is essential that the pad operate in as nearly as possible the same manner as relatively stiff pads when used on flat surfaces. If this action is not secured then the pad, even on flat surfaces, has to be applied to the work with considerable pressure to produce the desired cutting action, causing a considerable flexing and a resultant severe 30 wear on the abrasive disk tending both to break the backing of the disk and to loosen the grain of abrasive therefrom. The present pad is well adapted to the varied service for which it is intended. It has sufficient 35 rigidity to operate on flat surfaces without the use of any considerable pressure and is still sufficiently flexible to follow surfaces of considerable concavity when required and when the machine is applied to the surface 40 with heavy pressure.

45 Other modes of applying the principle of my invention may be employed instead of the one explained, change being made as regards the mechanism herein disclosed, provided the means stated by any of the following claims or the equivalent of such 50 stated means be employed.

I therefore particularly point out and distinctly claim as my invention:—

55 1. A supporting pad of the character described comprising a circular disk of tough, but relatively soft rubber provided with an exposed relatively flat work-engaging surface and with a layer of reinforcing material adjacent its other flat surface and having a supporting disk of smaller diameter concentrically disposed against said last-named surface and integrally united thereto.

60 2. A supporting pad of the character described comprising a circular disk of tough

but relatively soft rubber provided with an exposed relatively flat work-engaging surface and with a layer of reinforcing material adjacent its other flat surface and having a supporting disk of relatively rigid hard rubber disposed concentrically against said last-named surface and integrally united thereto.

Signed by me, this 10th day of November, 1928.

HERBERT R. STRATFORD.
